GEORGE P. CARROLL, OF BRIDGEPORT, CONNECTICUT.

AUTOMATIC COMPRESSION REFRIGERATING APPARATUS.

1,118,737.

Specification of Letters Patent.

Patented Nov. 24, 1914.

Application filed April 12, 1907. Serial No. 367,836.

To all whom it may concern:

Be it known that I, GEORGE P. CARROLL, a citizen of the United States, residing at Bridgeport, in the county of Fairfield and State of Connecticut, have invented a new and useful Automatic Compression Refrigerating Apparatus, of which the following is a specification.

My invention relates to improvements in compression refrigerating apparatus, especially those of small capacities where the attendance of an engineer would be impracticable. Such plants range, in their capacities, from plants adapted for domestic purposes, up to plants having a refrigerating capacity of 20 tons per 24 hours.

The means employed consist of automatic means whereby the quantity of refrigerating fluid passing through the expansion valve and the quantity of cooling fluid passing into the condenser and water jacket are made to correspond with the requirements of the system while the compressor is running, so as to make possible the maintenance of a predetermined temperature around the expansion coils; whereby the starting and stopping of the compressor is made to depend on the rise and fall of temperature, within predetermined limits, in the refrigerator inclosing the expansion coils; and whereby the power driving the compressor is shut off if an abnormal amount of power, indicating a dangerous condition, is required to drive the compressor.

While other refrigerating fluids may be used, it is to be understood in the following description that anhydrous ammonia is the fluid preferred, as on the whole it produces the most satisfactory results.

In the drawings, Figure 1 is a diagrammatic representation of my invention showing the parts in detail and their connections. Fig. 2 is a front elevation of an electric expansion valve and a vertical section of a pressure regulating valve with their connections. Fig. 3 is a side elevation of a switch shown in the preceding figure. Fig. 4 is a vertical section of said expansion valve. Fig. 5 is a vertical cross-section of an electric water valve with its connections. Fig. 6 is a front elevation of said water valve. And Fig. 7 is a vertical cross-section of a modified form of the valve shown in Fig. 5.

An expansion coil C is convoluted in a suitable compartment 1 of a refrigerator B. The coil may be used to refrigerate the air

in the compartment so that the air will circulate through the refrigerator after being directly chilled by the coil. Or a suitable brine may be placed in the compartment so that the coil will refrigerate the brine and the air will circulate through the refrigerator after being chilled by the brine. In the latter case the brine can be carried below the freezing point so as to freeze potable water in an ice can 2, placed so as to be surrounded by the brine.

The outlet end of the expansion coil C emerges from the refrigerator and leads into the inlet side of a compressor K, being intermediately provided with a back or low pressure gage L. The compressor is driven by a suitable motor, preferably an electric motor M, preferably through a belt. When the compressor is in operation it draws spent gas from the expansion coil, compresses it in the manner common to such machines, and forces the compressed gas through a high pressure pipe 4, intermediately provided with a head or high pressure gage H, through an oil separator O, and into a condenser D.

A pipe 5 leads from a source of water supply, is intermediately provided with an electric water valve W, and leads into the condenser D. The cooling water, by its contact with the walls of the passages containing the hot, compressed gas from the compressor, removes the heat of compression and condenses and liquefies the refrigerating fluid. From the condenser the pipe 5 leads to a water jacket 6 surrounding the compressor cylinders of the compressor K, where it removes a part of the heat of compression before passing off into the waste. In some constructions the cooling water is led first to the compressor water jacket and thence to the condenser; but the better practice is to reverse the order so that the coldest water may cool the coldest gas, thereby reducing the final pressure of the gas and making the head pressure less and the power required to operate the compressor correspondingly less. The condenser D and water jacket 6, with their connections, constitute fluid cooled means for condensing the compressed gas, although the water jacket may be omitted if desired.

From the condenser the pipe 4 transmits the liquefied fluid to a container F, and thence to an electric expansion valve E. From the valve E the inlet end of the ex-

pansion coil C leads through a pressure regulating valve P into the refrigerator B. In actual practice it is advisable to have the inlet side of the compressor K and the valve 5 E as near as practicable to the place to be refrigerated so as to prevent a useless refrigeration of the outside atmosphere. And the valve P, if made accessible for convenient adjusting, may be placed within the space to 10 be refrigerated; or, if a brine tank is used, as near to it as practicable. A stop valve 7 may be placed in the water supply pipe 5 ahead of the valve W and stop valves 8, 9, 10, 11, 12 and 13 may be placed at convenient 15 points in the ammonia circuit to disconnect parts of the system when desired. All these valves are to be open when the plant is to be operated for circulating the ammonia. When, however, a vacuum is to be pumped 20 in the system preliminary to charging, the valve 9 is closed, the valves 7, 8, 10, 11, 12 and 13 are opened, and an air valve 9^a, between the valve 9 and the delivery side of 25 the compressor K, is opened. After a vacuum has been pumped, the valve 9^a is closed, the compressor is stopped and the valve 9 is opened. An ammonia charging valve 14 is placed in the pipe 4 beyond the container F and the valve 12. A drain valve 15 is placed 30 at the lowest part of the pipe 5 to drain the water jacket and condenser when the plant is to be shut down for the season. From the bottom of the oil separator O a pipe 16 provided with a stop valve leads into the crank 35 chamber of the compressor K; this valve is to be kept closed except on the infrequent occasions when it is desired to drain the oil separator of accumulated oil.

From a generator G, located as at a central power station, mains 17 lead through a hand switch S to and back again from the motor M. Between the switch and the motor an automatic circuit breaker A, of any approved type, is placed to automatically 45 shut down the motor in case extremely abnormal conditions develop in the plant as manifested by the requirement of a very high current to operate the motor. Between the circuit breaker and the motor is placed 50 a starting rheostat R, having a solenoid 18.

The casing of the valve E has intermediate between its inlet and outlet ports a horizontal valve seat 19. A needle valve 20 is adapted to occupy and close the valve seat 19 from above and when not otherwise raised is pressed down upon its seat by a coiled spring 21, abutting at one end against the inside of the top cap 22 of the casing and at its other end against the top of the needle 55 valve. The upper part of the valve is provided with a projecting pin 23, adapted for engagement with the slotted end of an inner lever 24, extending in a horizontal direction. The other end of this lever is secured to or

made of one piece with a lever shaft 25, 65 journaled at one end in the back wall of the casing and passing out through the front of the casing where it is provided with a suitable stuffing box. An outer lever 26 is secured to the outer end of the lever shaft 70 and extends in a horizontal direction opposite to that of the inner lever.

Pivoted at 27 on the extended outside part of the casing of the valve E is a three-part lever 28 having its main arm 29 extending 75 horizontally toward and terminating in a position just above the outer end of the outer lever 26. The extreme end of the main arm 29 is provided with an adjusting screw 30 so that the contact of the main arm 29 and the outer end of the outer lever 26 may be suitably regulated. The length with which the screw projects below the main arm determines the depression of the outer lever 26 and the consequent elevation of the 80 inner lever 24, the pin 23, and the needle valve 20 from off its seat. Substantially at right angles to the main arm an upper arm 31 extends upward and a lower arm 32 extends downward from the pivot 27. 90

An electro-magnet 33 is placed immediately under the main arm 29 and when energized by the passage of a current depresses the main arm downward so as to be in contact through the adjusting screw 30 with the 95 outer end of the outer lever 26. The depression of the main arm 29 overcomes a spring 34 which keeps the main arm elevated when the magnet is not energized or when the main arm is not locked in a depressed position. The depression of the main arm 29 100 throws the upper arm 31 to the left and the lower arm 32 to the right.

A dog 35, pivoted at 36 on the extended outside part of the casing of the valve E, has 105 a tooth 37, which rests upon the inclined outside of the extreme top of the upper arm 31 while the main arm 29 is elevated. But with the depression of the main arm by the energizing of the electro-magnet 33, the upper arm 31 slips inside of the tooth 37 and there continues in a locked position after the electro-magnet 33 is no longer energized. A switch 38 is pivoted at 39 on the extended 110 outside part of the casing of the valve E and connects the electro-magnet 33 as herein-after stated. This switch has two limit arms 40 and 41 and also a weight arm intermediate between them and ending in a small globular weight 42. Both these limit arms 115 are adapted in turn to be engaged by the lower end of the lower arm 32 as it is moved to the right by the depression of the main arm 29 and back again by its elevation. When the electro-magnet 33 is energized, the 120 first effect of depressing the main arm 29 is to lock the upper arm 31 into engagement with the tooth 37; also the lower arm 32 is 125

thrown against the limit arm 40 so as to thrust it to the right and to throw the center of gravity of the weight 42 to the right of the center of the pivot 39. This shifting of the weight 42 then opens the switch and breaks the flow of current through the electro-magnet. The time required for this last action is sufficient to permit the upper arm 31 to become engaged with the tooth 37 before the current is broken.

A second electro-magnet 43 is secured to the upper part of the extended outside part of the casing of the valve E immediately above the dog 35. When the electro-magnet 43 is energized it lifts the dog and thereby releases the upper arm 31. This action permits the spring 34 to raise the main arm 29, the electro-magnet 33 being, as just seen, in a condition of non-energization. The lifting of the main arm 29 throws the lower arm 32 against the limit arm 41 so as to thrust it to the left and to throw the center of gravity of the weight 42 to the left of the center of the pivot 39. This shifting of the weight then closes the switch 38 and makes possible a flow of current to again energize the electro-magnet 33.

The pressure reducing valve P, interposed in the expansion coil C, preferably consists of a lower casing 44 having a perforated lateral entrance boss 45 and an outlet 46. To the top of the lower casing is bolted an upper casing 47 so as to secure between the flanges of the casings a diaphragm 48. A coiled spring 49 tends to force the diaphragm downward. An adjusting screw 50, extending through the top of the upper casing, is used to adjust the pressure of the spring. Secured to the under side of the diaphragm is a depending slotted bar 51. Threaded into the bar is a conical valve plug 52 extending up into its slot. An entrance piece 53 rests in the boss 45, having a central passage from its outer end terminating in a conical valve seat 54 on its under side adapted for the seating of the valve plug 52 when the diaphragm 48 and the depending slotted bar 51 are forced upward. The entrance piece is kept in its predetermined position preferably by set screws 55 piercing the valve casing.

The casing of the electric water valve W has an oblong port 56 with its longer axis vertical. A gate valve 57 is adapted to partially or wholly open the port according to its position of elevation. A valve stem 58 is secured at its lower end to the top of the valve and passes up and out through a detachable cap 59 closing the casing and being provided with a suitable stuffing box. A spring 60 coiled about the valve stem and abutting against the inside of the cap and the top of the valve keeps the valve closed when not opposed by a greater force. The valve stem 58 above the cap 59 is provided with,

say three, collar heads 61, 62 and 63, which should be longitudinally adjustable. In Fig. 5 the stem 58 is shown as threaded and all three collar heads are correspondingly threaded and are kept in any desired position by set screws. In the alternative construction shown in Fig. 7 the valve stem consists of a lower valve stem 58^a, having a threaded socket 64, and an upper valve stem 58^b correspondingly threaded at its lower end for longitudinal adjustment in the socket 64. In this latter construction only the lower collar heads 62^a and 63^a are threaded and provided with set screws; and the upper valve stem 58^b and the collar head 61^a receive their proper longitudinal position by a proper adjustment in the socket 64.

A solenoid 65 has a core 66 insulated at its top and provided with an arm 67 projecting at right angles from the core above the solenoid and below the insulated top. The outer end of the arm 67 has a vertical face. A dog 68, pivoted at 69 on an extension of the lower end of the core 66, has a lower arm 70 which, when the core 66 is in its lowest position, rests on a pin 71, supported by an extension of the cap 59, so as to keep the dog away from the valve stem. But when the core is elevated, a flat spring 72, attached at one end to the core 66, presses the dog against the valve stem or against one of its collar heads if one of these is adjacent.

A double switch arm 73, pivoted at the left of its center at 74, has an insulated flat spring 75 on its under side at the right of the pivot 74, and a coiled spring 76, attached to its upper side at the left of the pivot 74 and tending to keep in an elevated position the left end of the double switch arm. The arm is insulated between the pivot 74 and the spring 76. The right end of the arm beyond the flat spring 75 has a contact surface adapted to close a circuit on contact points 77 and 78, which are insulated from each other.

A double locking arm 79 pivoted at 80 by means of a tooth 81 projecting from the upper member of the locking arm, is adapted to engage the left end of the switch arm 73 from above, so as to hold the right end of the switch arm elevated away from the contact points 77 and 78. A coiled spring 82, attached to the lower member of the locking arm, tends to pull that member to the left so as to force the upper member and the tooth 81 to the right. When out of engagement the left end of the switch arm 73 rests on the upper face of the tooth 81. When the tooth 81 is engaged as shown with the left end of the switch arm 73 and also when that end rests on the upper face of the tooth, the outer face of the lower member of the locking arm 79 is in a vertical plane just a trifle to the left of the arm 67.

A detent lever 83, pivoted at 84 and supported by an extension of the cap 59, is normally kept in nearly a vertical position by a coiled spring 85 tending to pull it to the right. Just above the pivot 84 the detent lever 83 has a detent 86 adapted to engage from beneath and to lock in an elevated position whichever one of the adjacent collar heads it may be under. The extreme top of the detent lever 83 has a pin 87 adapted on occasion to engage and keep in position a lock extension 88 extending to the left from the upper member of the double locking arm 79. An electro-magnet 90 is operative when energized to pull the detent lever 83 to the left in opposition to the spring 85. From the mains 17, through a resistance 91, a branch line 92 leads to the solenoid 65. From the solenoid a line 93 leads to the contact point 78. A line 94 leads from the pivot 74 back to the mains 17 on the farther side of the motor M. A line 95 leads from the line 93 to a circuit breaker 96, of the usual kind, and thence through a resistance 97 having a core 98 back to the mains 17 also on the farther side of the motor M. The resistance 97 operates on the core 98 so as, by opening the circuit breaker, to break the circuit when the current exceeds a predetermined limit. The circuit breaker 96 is provided with a suitable arm 99, which serves the double purpose of being a hand lever for closing when lifted the circuit and also is adapted to be lifted with like effect by the elevation of a core 100 having a pin 101 for engaging the arm 99 when a solenoid 102 containing the core 100 is energized. A line 103 leads from the line 93 through a resistance 104 back to the mains 17 also on the farther side of the motor M. A branch line 105 leads to and through the solenoid 102 from the branch line 92 to the contact point 77. From the mains 17 between the automatic circuit breaker A and the contacts of the rheostat R through a resistance 106 a branch line 107 leads to and through the solenoid 18 to a contact point 108 where contact can be made through a hand switch 109 back to the generator G. Such a contact energizes the solenoid 18 of the rheostat R to turn on the full current for starting the motor M. The hand switch is also adapted to make contacts at 110 and 111 respectively. Through a resistance 112 a branch line 113 leads from the branch line 107 to the right of the resistance 106 to and through the electro-magnet 90 to the contact point 110. From the mains 17 between the rheostat R and the motor M a branch line 114 leads to and through the switch 38 and the electro-magnet 33 back to the mains on the farther side of the motor. From the branch line 113 between the resistance 112 and the electro-magnet 90 a branch line 115 leads to and through the electro-magnet 43 back to the

branch line 113 on the farther side of the electro-magnet 90.

Within the refrigerator B is mounted a thermostat T of any approved type. In the form shown it consists of a rod 116, subject to expansion and contraction with increases or decreases of temperature, attached to a lever 117 adapted to make electrical contact either at 118 or 119. A solenoid 120 contains a core 121 toothed at its top and having a switch 122 attached to its lower extremity. When the core is lifted by the temporary energization of the solenoid its tooth is normally engaged by a detent 123, which may, however, be drawn out of engagement with the tooth by the energization of an electro-magnet 124. From the branch line 107 between the solenoid 18 and the contact point 108 a branch line 125 leads to the mains 17 between the switch 109 and the generator, which branch line is closed when the switch 122 is elevated. From the branch line 113 between the resistance 112 and the electro-magnet 90 a branch line 126 leads to and through the solenoid 120 to the contact point 118. The lever 117 being conductive from its extremity to its pivot 127, a branch line 127a leads from the pivot to the contact point 111. From the branch line 126 between the resistance 112 and the solenoid 120 a branch line 128 leads to and through the electro-magnet 124 to connect at 129 with the branch line 113 between the electro-magnet 90 and the contact point 110; and thence the branch line 128 leads to the contact point 119.

The parts are so constructed in relation to each other that a greater current is required to pass through the resistance 104 than through the resistance 97 and the automatic circuit breaker A does not become operative until after the passage of a current through the resistance 104 has failed of its intended purpose as hereinafter explained. There are therefore three means as shown for turning on and increasing the supply of condenser water: (1) by a current through the contact 78 and the line 94; (2) by a greater current through the resistance 97; and (3) by a still greater current through the resistance 104. If this last fails to supply a sufficiency of cooling water, as by the total failure of water supply, causing an excessive power to operate the machine; then the circuit breaker A becomes operative to shut off the current and to stop the machine.

The method of operation is as follows: Before starting the compressor for the station, the valve 7 is opened and, until the condenser D and the water jacket 6 are filled, the valve stem 58 is held by hand in an elevated position. The coiled spring 21 is now (as a second condition) holding depressed the needle valve 20 and the coiled spring 60 is also holding depressed the gate valve 57, 125

the collar head 61 being below the detent 86 and the left end of the double switch arm 73 resting on top of the tooth 81. It is first assumed that the plant is operated without the use of a thermostat. In that case the hand switch S is closed and the hand switch 109 is brought to contact at 108. This action permits a slight current to flow through the automatic cut off A, the resistance 106, the branch line 107, the solenoid 18, the contact point 108, and the hand switch 109 back to the generator G. The energization of the solenoid 18 actuates the rheostat R and closes the circuit to the motor M and thus starts the compressor K. Simultaneously through the branch line 114, the switch 38 and the electro-magnet 33 back to the mains 17, a slight current energizes the electro-magnet 33 and thus, through the connections to the needle 20 valve 20, opens the valve E; and at the same time through the resistance 91, the branch line 92, the solenoid 65, the line 93, the contact point 78, the double switch arm 73 (being then in contact with the contact points 77 and 78) and the line 94 back to the mains 17, a slight current energizes the solenoid 65 and thus acts upon the core 66 and the dog 68, which is pressed against the valve stem 58 by the spring 72 as soon as lifted from the pin 71, to act upon the collar head 61 and by lifting the valve stem 58 to open the valve W. The plant is thus in operation either for pumping a vacuum, as will be indicated by both gages L and H, preliminary to charging with ammonia; or, if that has already been done, for doing the work of refrigeration, the liquid ammonia vaporizing as it passes through the valve E and condensing water being supplied through the 40 valve W. The charging of the system, after a vacuum has been pumped and the air valve 9^a has been closed and the valve 9 has been opened, is accomplished, the compressor running slowly on part current, by connecting a 45 drum of anhydrous ammonia to the pipe having the valve 14, by closing the valve 12, by opening the valve 14, and by slightly opening the outlet valve on the drum. During this process the valve 14 is manipulated 50 as a hand expansion valve so as to gradually charge the system, the ammonia finally becoming liquefied in the container F. The valve E does not interfere with this process as it remains constantly open while the compressor is running. Nor does the valve P 55 interfere because the process of charging is carried on with a low back pressure; and if, by any accident the back pressure should be excessive, the valve P would operate as a safety device to prevent liquid ammonia 60 passing into the compressor.

The employment of current in opening the valves E and W is only instantaneous. For the depressing of the main arm 29, 65 when the electro-magnet 33 is energized, ro-

tates the upper arm 31 to the left on the pivot 27 until the three-arm lever 28 is locked in position by the dog 35 through its tooth 37; and at the same time the lower arm 32 is rotated to the right. The consequent engagement of the lower arm with the limit arm 40 and the thrusting of the weight 42 to the right of the center of the pivot 39 opens the switch 38 and shuts off the flow of current through the branch line 114. And the lifting of the core 66 lifts the collar head 61 and through it forces the detent 86 and the detent lever 83 to the left, overcoming the coiled spring 85 in so doing. Just as soon as the collar head 61 passes the detent 86, the coiled spring 85 forces the detent 86 against the stem 58 under the collar head 61, thus locking the valve stem and the valve in a partially open position as shown. As the core 66 is being elevated and before the detent lever is forced to the left, the insulated top of the core strikes the insulated flat spring 75 and thereby tends to break the contact of the double switch arm 73 with the contact points 77 and 78. But at the instant of striking, the face of the arm 67 is just opposite the face of the lower member of the double locking arm 79 and thereby holds the tooth 81 so that the left end of the double switch arm cannot drop below the tooth. An instant later, however, the arm 67 has passed above the lower member of the double locking arm 79 and the core 66 has fully compressed the flat spring 75 so that the current through the contact points 77 and 78 will be completely broken as soon as the tooth 81 can be forced to the left. The tooth is so forced to the left an instant later by the down pressure upon it of the left end of the double switch arm 73 and especially by the movement to the left of the pin 87 along the lock extension so as to depress the lock extension 88 as the detent lever 83 rotates to the left on its pivot 84. This rotation takes place, as just stated, while the collar head 61 is passing the detent 86. The breaking of the current under normal conditions deenergizes the solenoid 65 so that the core 66 and its dog 68 resume their original position. All the parts are now in the position shown in Fig. 5. The effect of this entire operation is to leave the collar head 61 locked by the detent 86, the valve W open to a normal degree and the current through the branch line 92 broken.

It is apparent that by properly adjusting the screw 30 the valve E can be opened sufficiently to permit of the transmission of the maximum quantity of ammonia required by the system. And a similar adjustment of the collar head 61, or, if the structure shown in Fig. 7 is used, of the upper valve stem 58 in the socket 64, will provide for a normal sufficiency of condensing water. The bottom collar head 63 or 63^a is adjusted low

- enough on the valve stem so that, when it is lifted by the dog 68, it will lift the gate valve 57 to the point permitting of the maximum flow of water needed for the condenser 5 D and the water jacket 6 even under unusual conditions. The one or more intermediate collar heads 62 or 62^a may then be adjusted so that all the collars will be equidistant on the stem. For every temperature 10 to be maintained in the expansion coil C (which will be about 10°, more or less, lower than the temperature to be maintained outside of the coil in the compartment 1) there is, as shown by the "ammonia tables," a corresponding maximum density and pressure. This maximum decreases with the decrease of the temperature to be maintained. Thus while a gage pressure of about 28 lbs. would 15 make possible a temperature in the coil only down to $\times 15^{\circ}$ F., a gage pressure of about 6 lbs. would make possible a temperature in the coil as low as -15° F. It is impossible, however, to permanently adjust such a valve as E, or any hand operated valve, so as to 20 obviate overfeeding or underfeeding.
- In case of underfeeding, the system does not operate to its full capacity nor at its highest efficiency for the temperature to be maintained. In case of overfeeding: 1. 25 The expansion coil is likely to frost outside of the refrigerator at the return end, beginning from the valve 8 and thence oftentimes as far as the compressor itself, at the expense of the efficiency of the plant. 2. 30 Liquid ammonia may be thus conveyed into the compressor cylinder, producing a dangerous situation similar to that where water from the boiler is carried into a steam engine cylinder. 3. As just seen, if the vapor 35 is too dense, it is impossible to produce the desired lowness of temperature in the coil. Therefore the valve E is adjusted to permit of the maximum density and then, to limit the density of the vapor in the greater part 40 of the coil, the pressure regulating valve P is provided. By the opening of the electric expansion valve E, the ammonia is permitted to vaporize and to become as dense as may be in that part of the expansion coil C between the valve E and the valve P. But 45 in all of the expansion coil lying beyond the valve P the density of the vapor is automatically limited, to any degree of density required, by properly adjusting the screw 50. 50 When the vapor becomes sufficiently dense it tends to overcome the force of the coiled spring 49, as adjusted by the position of the screw 50, to lift the diaphragm 48 and the bar 51 so as to force the valve 52 to its seat, 55 and thus to check the flow of ammonia. But as the gas in the expansion coil C is being at the same time drawn off by the compressor K, the tension of the gas upon the diaphragm tends to diminish so as to permit 60 the coiled spring to force the valve down-

ward. These two opposing tendencies continue to regulate the position of the valve so long as the valve E is open. In practice the valve P through its screw is first adjusted to produce the desired temperature in that 70 part of the expansion coil lying beyond it. This is done by trial, observing the back pressure gage L, and in view of the known relation between pressure and temperature as shown in the tables. The valve E is then 75 adjusted so that, when open, vaporization will occur between itself and the valve P.

The use of the pressure regulating valve P alone as an expansion valve would not produce certain desirable results obtained 80 with a hand regulated expansion valve when attended by an engineer. For when a non-automatic compressor is to be stopped, the best practice requires the engineer to shut off the hand expansion valve and let the compressor run a few strokes until the back pressure gage indicates a few pounds above 85 vacuum. By thus shutting off the expansion coils he relieves them from strain. The same result is accomplished with my invention. 90 For the turning off of the power, as will be described, permits the valve E to close at once; but the momentum of the moving parts causes a few more strokes of the compressor K until the back pressure is carried 95 down to a low point. As the delivery valve leading from the compressor K to the high pressure pipe 4 is, according to the usual practice, a spring check valve, no gas can 100 return; and the expansion coil and the compressor cylinder remain under low pressure so long as the compressor is inactive. Then when the current is turned on, the valve E opens immediately and the liquid ammonia begins to vaporize immediately 105 into the expansion coil C; and the compressor K draws out the spent gas as fast as it passes through the coil. If the pressure regulating valve P was used as an expansion valve, a relatively high pressure would 110 be maintained in the low pressure side of the system while standing idle. Furthermore, on starting up, there would be much more spent gas to be drawn from the expansion coil before the working fluid could begin 115 to refrigerate.

The condensation of a gas such as ammonia depends on two factors; namely, the pressure to which the gas is subjected and the heat of the gas as compressed. If it is 12 driven into a condenser sufficiently supplied with cooling water, it will liquefy at a comparatively low pressure, say 160 to 180 lbs. But if the condenser water is insufficient in quantity or too warm, liquefaction takes 12 place at a higher pressure. In this latter condition, the pressure of the gas in the pipe 4 beyond the delivery valve of the compressor K, is very high. Consequently to overcome such excessive pressure so as to 13

deliver gas from the compressor into the pipe 4, much more power is required to operate the motor M.

The greater the quantity of condensing water supplied to a refrigerating system, the less is the power required to operate the compressor. But in every plant depending for its power directly or indirectly upon the consumption of fuel, a point is reached where the increased cost of the water supplied, if metered, overbalances the saving in power. The point of maximum economy can be determined by experience, in view of the relative cost of power and water. My invention makes it possible to maintain the ascertained economic ratio, varying with different plants according to the cost of power and water, between the quantity of condensing water and the amount of power required to operate the compressor. This is accomplished for ordinary conditions, as before stated, by regulating the initial lift of the gate valve 57 through the collar head 61 or the valve stem 58^b. But sometimes it happens that the current required to drive the motor M increases beyond what would be sufficient to pass through the resistance 91 alone and becomes sufficient to pass through the branch line 92, the solenoid 65, the line 93, the line 95, the circuit breaker 96 and the resistance 97 back to the mains 17. This would occur while the motor M was running and when the supply of water passing into the condenser D, by reason of becoming heated in its source of supply, had become insufficient to remove enough of the heat of compression for the economical operation of the plant. In other words this would occur when, as indicated by the high pressure gage H, the supply of water was insufficient to keep down the head pressure to the point of economical operation.

The effect of a current passing through the resistance 97 is to again energize the solenoid 65, to lift the core 66, to engage the dog 68 with the collar head 62 so as to lift the stem 58 still higher until the collar head 62 gets above the detent 86 and is held by it in a locked position. At this time the only action of the core 66 on the flat spring 75 is to keep the double switch arm 73 from off the contact points 77 and 78 until the detent 86 locks the collar head 62 on its under side, when the tooth 81 again becomes operative to lock the double switch arm. As the gate valve 57 is lifted up to a position corresponding to that of the collar head 62 over the detent 86, the supply of water to the condenser is correspondingly increased. The normal effect of such an increased supply of condensing water is to decrease the power required to operate the motor M. Consequently, when this point is reached, the current no longer passes through the resistance 97; and the valve remains locked in its

secondary lifted position, and without the expenditure of power, until the current is shut off from the motor and the valve is closed in the manner hereinafter explained. But should it happen, from the continued heating of the water in its source of supply or from any other reason, that this increased supply of water is insufficient to reduce the power operating the motor and the power continues to increase, the current passing through the resistance 97 will soon lift the core 98 so as to act on the circuit breaker 96 and thereby break the current flowing through the resistance. By this action the arm 99 drops on the point 101. Under these circumstances, also, the valve remains locked in its secondary lifted position, and without the expenditure of power, until the current is shut off from the motor and the valve is closed. In other words this further opening of the valve either brings the power back to normal and so prevents power from being used to hold open the valve; or, if the power is not brought back to normal, the power is automatically shut off from the solenoid 65 so as no longer to be employed in holding the valve open.

Should the power required to operate the motor continue to increase beyond the point sufficient to open the circuit breaker 96, a branch current will eventually pass through the branch line 92, the solenoid 65, the line 93, the line 103 and the resistance 104 back to the mains 17. The energization of the solenoid 65 again lifts the core 66 and in consequence the dog 68 engages the collar head 63 and lifts the stem 58 to its highest elevation until the collar head 63 gets above the detent 86 and is held by it in a locked position. Here again the only effect of the core 66 on the flat spring 75 is to keep the double switch arm 73 from off the contact points 77 and 78 until the tooth 81 again interlocks with it. It will be observed that, under these circumstances, while some current continues to pass through the resistance 104, no current is employed in holding the valve lifted to its highest position. And if the increased flow of water is normally operative to decrease the current required to operate the water, the current will cease to flow through the resistance 104. If on the other hand, the current through the resistance should continue to increase, such a fact is proof that the difficulty does not lie with any ordinary insufficiency of water supply; but that something more serious is responsible.

The automatic circuit breaker A is so constructed and adjusted that the current from the generator G passes freely through the mains 17 until from some cause a normal current becomes insufficient to operate the motor M. It is to be understood, in this connection, that a current which merely re-

sults in actuating the valve W, by passing through the resistance 104, so as to permit of a maximum quantity of water flowing through the condenser and water jacket, is simply normal. When, however, the current has exceeded the limit where the maximum quantity of condensing water might remedy the difficulty, a dangerous condition is reached such that the compressor should be stopped until the cause of the difficulty can be ascertained and the trouble be remedied. Such an excess of current may indicate one or more of several conditions: 1. Breakage or disarrangement of parts in the motor itself. 2. Breakage or disarrangement of parts in the compressor. The most common accident of this nature is where the delivery valve of a compressor cylinder breaks and one of the pieces lodges against the cylinder head in the path of the advancing piston. 3. Abnormally high head pressure necessitating an excessive current for the operation of the motor. This may arise from the shutting off of the water supply in the water mains. 4. The passage of liquid ammonia into the compressor cylinder. This might happen if the valve E or the valve P should be improperly adjusted or should get out of order so that more liquid should pass into the expansion coil than could be vaporized. In any of these cases the automatic circuit breaker acts in the usual way to cut off all current from the system.

When it is desired to stop the compressor, the switch 109 for an instant is moved to make contact at 110 and then is moved where it will make none of the contacts shown. The breaking of the contact at 108 stops the flow of current through the resistance 106, the branch line 107 and the solenoid 18. The deenergization of the solenoid breaks the main current through the rheostat R and thus stops the motor M. The instantaneous contact at 110 sends a current through the resistance 112, the branch line 113, the electro-magnet 90 and the contact point 110 back to the mains 17. The consequent energization of this electro-magnet draws the detent lever 83 to the left and thus disengages whichever one of the adjacent collar heads is being held by the detent 86. This disengagement permits the coiled spring 60 to depress the gate valve 57 and to close the valve W, thus shutting off the supply of water at the same time that the power is turned off from the motor and compressor. Simultaneously with the release of any collar head, the rotation of the detent lever 83, through its pin 87 acting on the lock extension 88, moves the tooth 81 to the left. The double switch arm 73 is then acted upon by the coiled spring 76 so that it again makes contact with the contact points 77 and 78; but as the rheostat is now open no current passes to the motor M. When sub-

sequently the current is turned on to the motor, at the same time, as before explained, that the solenoid 65 is first energized by a current passing through the contact point 78, a current also passes through the line 105, the solenoid 102, and the contact point 77 to the double switch arm 73, there uniting with the current passing through the contact point 78. This energization of the solenoid 102 lifts the core 100 and the pin 101 and thereby lifts the main arm 99 so that the circuit breaker 96 is again put in operative position. The contact at 110 also sends a current through the branch line 115 to and through the electro-magnet 43 back to the branch line 114. The consequent energization of the electro-magnet 43 elevates the dog 35 and thus releases the upper arm 31 so that the coiled spring 34 elevates the main arm 29 and thus permits the coiled spring 21 to act on the needle valve 20 so as to close the valve E, also at the same time that the power is turned off from the motor and compressor. The elevation of the main arm 29 moves the lower arm 32 to the left and thus throws the limit arm 41 and the weight 42 to the left so as again to close the switch 38. It is apparent that when the plant is thus operated by the hand switch 109, the construction can be simplified by substituting a hand operated rheostat for the rheostat R and by eliminating the resistance 106, the branch line 107 and the contact point 108, leaving the hand switch 109 for making contact at 110 for an instant as before when it is desired to shut down the plant.

The parts shown and described of the valve W constitute a three stage valve. It is obvious that, if desired, the collar head 63, the line 103, the resistance 104, the line 105, the solenoid 102, the core 100, the pin 101 and the contact point 77 may be dispensed with. When an excess current passing through the resistance 97 opens the circuit breaker 96, the arm 99 will then be useful to subsequently close the circuit breaker by hand. Under these circumstances the valve has two stages and only two collar heads are necessary. It is also obvious that by the insertion of more collar heads, intermediate resistances, circuit breakers, solenoids and their connections, the number of stages of the valve may be increased above three. On the other hand, by the omission of the collar head 63, the line 95, the circuit breaker 96, the arm 99, the resistance 97, the line 105, the solenoid 102, the core 100, the pin 101 and the contact point 77, the valve is of a very simple two stage type.

In connection with the automatic circuit breaker A, an automatic gong or some other form of automatic signaling device may be used to call attention to the breaking of the circuit when such a condition occurs. This

circuit breaker as shown is constructed and operated essentially as is the circuit breaker 96 when operated by hand through the arm 99.

- 5 When the system is thermostatically operated all of the above modifications are possible except that the automatic rheostat R with its solenoid 18, or the equivalent thereof, must be employed. When the thermostatic 10 switch 109 is used the only function of the hand switch 109 is to make continuous contact at 111. The contact points 118 and 119 are adjustable so that, if for instance, the temperature in the refrigerator B rises to 39°, 15 the expansion of the rod 116 will rotate the lever 117 on its pivot 127 so as to make contact at 118; and a fall of temperature to 36° will rotate the lever to make contact at 119. By closing the hand switch S, when the 20 plant is to be operated, a current passes through the mains 17, the automatic circuit breaker A, the resistance 112, the branch line 126, the solenoid 120, the contact point 118, the lever 117, the pivot 127, the line 127^a, the contact 111, and the switch 109 back to the generator G. The consequent 25 energization of the solenoid 120 lifts the core 121 into holding engagement with the detent 123 and also closes the switch 122. The 30 closing of the switch causes a current to pass through the resistance 106, the branch line 107, the solenoid 18, the switch 122 and the line 125 back to the generator. The consequent 35 energization of the solenoid 18 starts the motor M and opens the valves E and W in the same manner as before. As the temperature falls in the refrigerator the rod 116 contracts until the contact between the lever 117 and the contact point 118 is broken. 40 Thereupon current no longer passes through the solenoid 120; but the core 121 continues to be held in its lifted position by the detent 123, so that current through the switch 122 still continues to energize the solenoid 18 45 and consequently the plant continues in operation. When, however, a further contraction of the rod 116, say after an hour's run or less, results in a contact of the lever 117 with the contact point 119, a current then 50 passes through the resistance 112, the electro-magnet 124, the line 128, the connecting point 129, the contact point 119, the lever 117, the pivot 127, the line 127^a, the contact 111, and the switch 109 back to the generator. The consequent 55 energization of the electro-magnet 124 withdraws the detent 123 from engagement with the tooth of the core 121, allowing the switch 122 to drop and thus to break the current through the line 125. This breaking of current deenergizes 60 the solenoid 18 so that the rheostat R now shuts off the current from the motor M and stops the compressor K. Simultaneously a 65 current passes through the resistance 112, the branch line 113, the electro-magnet 90,

and also through the branch line 115 and the electro-magnet 43, to the connecting point 129, where it unites with the other current back to the generator. The consequent energization of the electro-magnets 43 70 and 90 closes the valves E and W in the same manner as before. When the temperature has risen sufficiently, contact at 119 is broken and as it continues to rise the lever 117 moves over toward the contact point 118 75 to repeat the cycle of operations.

While in the drawings only one refrigerating chamber is shown, yet several chambers may have their separate expansion coils branching from the main coil C at it leaves 80 the valve P. Hand valves may be placed in each branch coil near the point of branching so that, by partially closing each valve sufficiently, the proper proportion of ammonia may pass into each compartment coil. In 85 such an arrangement the thermostat T would be placed in the compartment where an exact conformity to a predetermined temperature was most important. If necessary, to prevent the gas being drawn out too 90 rapidly by the compressor from any one or more of the branch coils, a similar valve can be placed in each such coil near its return to the compressor.

The valve E is made the subject of claims 95 in my application Ser. No. 360,055, filed March 1, 1907, entitled Electric expansion valve. A valve similar in some details to the valve P is shown in my application Ser. No. 351,068, entitled Automatic expansion 100 valve. The valve W is made the subject of claims in my application Ser. No. 364,418, filed March 25, 1907, entitled Electric water valve.

I claim:

1. In combination an apparatus for drawing in gas and compressing the same, a condenser leading from said apparatus, means for applying power to operate said apparatus, an expansion valve leading from said condenser, a pipe for admitting a cooling fluid to said condenser, a condenser valve controlling said pipe, automatic means for applying power to open said condenser valve and to vary the extent to which it is opened according to the amount of power applied in operating said apparatus, and automatic means for subsequently closing said condenser valve when the operation of said apparatus is terminated.

2. In combination an expansion coil, an apparatus adapted to draw gas therefrom and to compress the same, a condenser leading from said apparatus, means for applying power to operate said apparatus, an expansion valve leading from said condenser into said coil, a pipe for admitting a cooling fluid to said condenser, a condenser valve controlling said pipe, automatic means for applying power to open said condenser valve 125 and to vary the extent to which it is opened according to the amount of power applied in operating said apparatus, and automatic means for subsequently closing said condenser valve 130 when the operation of said apparatus is terminated.

and to vary the extent to which it is opened according to the amount of power applied in operating said apparatus, and automatic means for subsequently closing said condenser valve when the operation of said apparatus is terminated.

3. In combination an apparatus for drawing in gas and compressing the same, a condenser leading from said apparatus, means for applying power to operate said apparatus, an expansion valve leading from said condenser, a pipe for admitting a cooling fluid to said condenser, a condenser valve controlling said pipe, automatic means for applying power to open said condenser valve and to vary the extent to which it is opened according to the amount of power applied in operating said apparatus, automatic means operated by such power to shut off the power so applied in relation to said condenser valve, and automatic means for subsequently closing said condenser valve when the operation of said apparatus is terminated.

4. In combination an expansion coil, an apparatus adapted to draw gas therefrom and to compress the same, a condenser leading from said apparatus, means for applying power to operate said apparatus, an expansion valve leading from said condenser into said coil, a pipe for admitting a cooling fluid to said condenser, a condenser valve controlling said pipe, automatic means for applying power to open said condenser valve and to vary the extent to which it is opened according to the amount of power applied in operating said apparatus, automatic means operated by such power to shut off the power so applied in relation to said condenser valve, and automatic means for subsequently closing said condenser valve when the operation of said apparatus is terminated.

5. In combination an apparatus for drawing in gas and compressing the same, a condenser leading from said apparatus, means for applying power to operate said apparatus, an expansion valve leading from said condenser, a pipe for admitting a cooling fluid to said condenser, a condenser valve controlling said pipe, a thermostat operative at a high temperature limit to apply power to open said condenser valve and at a low temperature limit to apply power to close said condenser valve, and automatic means operated by the power applied to open said condenser valve to vary the extent to which it is opened according to the amount of power applied in operating said apparatus.

6. In combination an expansion coil, an apparatus adapted to draw gas therefrom and to compress the same, a condenser leading from said apparatus, means for applying power to operate said apparatus, an expansion valve leading from said condenser into said coil, a pipe for admitting a cooling

fluid to said condenser, a condenser valve controlling said pipe, a thermostat operative at a high temperature limit to apply power to open said condenser valve and at a low temperature limit to apply power to close said condenser valve, and automatic means operated by the power applied to open said condenser valve to vary the extent to which it is opened according to the amount of power applied in operating said apparatus.

7. In combination an apparatus for drawing in gas and compressing the same, a condenser leading from said apparatus, means for applying power to operate said apparatus, an expansion valve leading from said condenser, a pipe for admitting a cooling fluid to said condenser, a condenser valve controlling said pipe, automatic means for applying power to open said condenser valve and to vary the extent to which it is opened according to the amount of power applied in operating said apparatus, automatic means operated by the power applied to open said condenser valve to shut off the power applied in relation to said valve, and automatic means for subsequently closing said condenser valve when the operation of said apparatus is terminated.

8. In combination an expansion coil, an apparatus adapted to draw gas therefrom and to compress the same, a condenser leading from said apparatus, means for applying power to operate said apparatus, an expansion valve leading from said condenser into said coil, a pipe for admitting a cooling fluid to said condenser, a condenser valve controlling said pipe, automatic means for applying power to open said condenser valve and to vary the extent to which it is opened according to the amount of power applied in operating said apparatus, automatic means operated by the power applied to open said condenser valve to shut off the power applied in relation to said valve, and automatic means for subsequently closing said condenser valve when the operation of said apparatus is terminated.

9. In combination an apparatus for drawing in gas and compressing the same, a condenser leading from said apparatus, an expansion valve leading from said condenser, a pipe for admitting a cooling fluid to said condenser, a condenser valve controlling said pipe, automatic means for applying power to open said condenser valve, to start the operation of said apparatus and to vary the extent to which the condenser valve is opened according to the amount of power applied in operating said apparatus, and automatic means for subsequently closing said condenser valve and terminating the operation of said apparatus.

10. In combination an expansion coil, an apparatus adapted to draw gas therefrom and to compress the same, a condenser lead-

ing from said apparatus, an expansion valve leading from said condenser into said coil, a pipe for admitting a cooling fluid to said condenser, a condenser valve controlling said pipe, automatic means for applying power to open said condenser valve, to start the operation of said apparatus and to vary the extent to which the condenser valve is opened according to the amount of power applied in operating said apparatus, and automatic means for subsequently closing said condenser valve and terminating the operation of said apparatus.

11. In combination an apparatus for drawing in gas and compressing the same, a condenser leading from said apparatus, an expansion valve leading from said condenser, a pipe for admitting a cooling fluid to said condenser, a condenser valve controlling said pipe, automatic means for applying power to open said condenser valve, to start the operation of said apparatus and to vary the extent to which the condenser valve is opened according to the amount of power applied in operating said apparatus, automatic means operated by the power applied to open said condenser valve to shut off the power applied in relation to said valve, and automatic means for subsequently closing said condenser valve and terminating the operation of said apparatus.

12. In combination an expansion coil, an apparatus adapted to draw gas therefrom and to compress the same, a condenser leading from said apparatus, an expansion valve leading from said condenser into said coil, a pipe for admitting a cooling fluid to said condenser, a condenser valve controlling said pipe, automatic means for applying power to open said condenser valve, to start the operation of said apparatus and to vary the extent to which the condenser valve is opened according to the amount of power applied in operating said apparatus, automatic means operated by the power applied to open said condenser valve to shut off the power applied in relation to said valve, and automatic means for subsequently closing said condenser valve and terminating the operation of said apparatus.

13. In combination an apparatus for drawing in gas and compressing the same, a condenser leading from said apparatus, an expansion valve leading from said condenser, a pipe for admitting a cooling fluid to said condenser, a condenser valve controlling said pipe, a thermostat operative at a high temperature limit to apply power to open said condenser valve and to start the operation of said apparatus and at a low temperature limit to apply power to close said condenser valve and to terminate the operation of said apparatus, and automatic means operated by the power applied to open said condenser valve to vary the extent to

which it is opened according to the amount of power applied in operating said apparatus.

14. In combination an expansion coil, an apparatus adapted to draw gas therefrom and to compress the same, a condenser leading from said apparatus, an expansion valve leading from said condenser into said coil, a pipe for admitting a cooling fluid to said condenser, a condenser valve controlling said pipe, a thermostat operative at a high temperature limit to apply power to open said condenser valve and to start the operation of said apparatus and at a low temperature limit to apply power to close said condenser valve and to terminate the operation of said apparatus, and automatic means operated by the power applied to open said condenser valve to vary the extent to which it is opened according to the amount of power applied in operating said apparatus.

15. In combination an expansion coil, a compressor to draw gas therefrom and to compress the same, fluid cooled means for condensing the compressed gas, a pipe for supplying cooling fluid to said means, an expansion valve for transmitting the condensed fluid into said coil, a condenser valve controlling said pipe, automatic means for opening said condenser valve and for locking it open and further operative when the power driving said compressor exceeds a predetermined limit to further open said condenser valve and to subsequently close it.

16. In combination an expansion coil, a compressor to draw gas therefrom and to compress the same, fluid cooled means for condensing the compressed gas, a pipe for supplying cooling fluid to said means, an expansion valve for transmitting the condensed fluid into said coil, a condenser valve controlling said pipe, automatic means for opening said condenser valve and for locking it open and further operative when the power driving said compressor exceeds a predetermined limit to further open said condenser valve, to lock it open and to subsequently close it.

17. In combination an expansion coil, a compressor to draw gas therefrom and to compress the same, an electric motor for driving said compressor, fluid cooled means for condensing the compressed gas, a pipe for supplying cooling fluid to said means, an expansion valve for transmitting the condensed fluid into said coil, a condenser valve controlling said pipe, automatic means for applying electric power to open said condenser valve and to lock it open and when the power driving said motor exceeds a predetermined limit to further open said condenser valve and to subsequently close it.

18. In combination an expansion coil, a compressor to draw gas therefrom and to compress the same, an electric motor for

driving said compressor, fluid cooled means for condensing the compressed gas, a pipe for supplying cooling fluid to said means, an expansion valve for transmitting the 5 condensed fluid into said coil, a condenser valve controlling said pipe, automatic means for applying electric power to open said condenser valve and to lock it open and when the power driving said motor exceeds 10 a predetermined limit to further open said condenser valve, to lock it open and to subsequently close it.

19. In combination an expansion coil, a compressor to draw gas therefrom and to 15 compress the same, fluid cooled means for condensing the compressed gas, a pipe for supplying cooling fluid to said means, an expansion valve for transmitting the condensed fluid into said coil, a condenser valve 20 controlling said pipe, automatic means for opening said condenser valve when said compressor is started and for locking it open and further operative when the power driving said compressor exceeds a predetermined limit to further open said condenser valve and to subsequently close it.

20. In combination an expansion coil, a compressor to draw gas therefrom and to compress the same, fluid cooled means for 30 condensing the compressed gas, a pipe for supplying cooling fluid to said means, an expansion valve for transmitting the condensed fluid into said coil, a condenser valve controlling said pipe, automatic means for 35 opening said condenser valve when said compressor is started and for locking it open and further operative when the power driving said compressor exceeds a predetermined limit to further open said condenser valve, to lock it open and to subsequently close it.

21. In combination an expansion coil, a compressor to draw gas therefrom and to compress the same, an electric motor for 45 driving said compressor, fluid cooled means for condensing the compressed gas, a pipe for supplying cooling fluid to said means, an expansion valve for transmitting the condensed fluid into said coil, a condenser valve 50 controlling said pipe, automatic means for applying electric power to open said condenser valve when said motor is started and for locking it open, when the power driving said motor exceeds a predetermined limit to further open said condenser valve, and for subsequently closing it.

22. In combination an expansion coil, a compressor to draw gas therefrom and to compress the same, an electric motor for 60 driving said compressor, fluid cooled means for condensing the compressed gas, a pipe for supplying cooling fluid to said means, an expansion valve for transmitting the condensed fluid into said coil, a condenser valve 65 controlling said pipe, automatic means

for applying electric power to open said condenser valve when said motor is started and for locking it open, when the power driving said motor exceeds a predetermined limit for further opening said condenser 70 valve and for locking it open, and for subsequently closing it.

23. In combination an expansion coil, a compressor to draw gas therefrom and to compress the same, fluid cooled means for 75 condensing the compressed gas, a pipe for supplying cooling fluid to said means, an expansion valve for transmitting the condensed fluid into said coil, a condenser valve controlling said pipe, automatic means for 80 opening said condenser valve and for locking it open and further operative when the power driving said compressor exceeds a predetermined limit to further open said condenser valve and to close it when said compressor is stopped.

24. In combination an expansion coil, a compressor to draw gas therefrom and to compress the same, fluid cooled means for condensing the compressed gas, a pipe for 90 supplying cooling fluid to said means, an expansion valve for transmitting the condensed fluid into said coil, a condenser valve controlling said pipe, automatic means for opening said condenser valve and for locking it open and further operative when the power driving said compressor exceeds a predetermined limit to further open said condenser valve, to lock it open and to close it when said compressor is stopped. 95

25. In combination an expansion coil, a compressor to draw gas therefrom and to compress the same, an electric motor for driving said compressor, fluid cooled means for condensing the compressed gas, a pipe 105 for supplying cooling fluid to said means, an expansion valve for transmitting the condensed fluid into said coil, a condenser valve controlling said pipe, automatic means for applying electric power to open said condenser valve and for locking it open, when the power driving said motor exceeds a predetermined limit for further opening said condenser valve, and for closing it when said motor is stopped. 110

26. In combination an expansion coil, a compressor to draw gas therefrom and to compress the same, an electric motor for driving said compressor, fluid cooled means for condensing the compressed gas, a pipe 120 for supplying cooling fluid to said means, an expansion valve for transmitting the condensed fluid into said coil, a condenser valve controlling said pipe, automatic means for applying electric power to open said condenser valve and for locking it open, when the power driving said motor exceeds a predetermined limit for further opening said condenser valve and locking it open, and for closing it when said motor is stopped. 125

27. In combination an expansion coil, a compressor to draw gas therefrom and to compress the same, fluid cooled means for condensing the compressed gas, a pipe for supplying cooling fluid to said means, an expansion valve for transmitting the condensed fluid into said coil, a condenser valve controlling said pipe, automatic means for opening said condenser valve when said compressor is started and for locking it open and further operative when the power driving said compressor exceeds a predetermined limit to further open said condenser valve and to close it when said compressor is stopped.
28. In combination an expansion coil, a compressor to draw gas therefrom and to compress the same, fluid cooled means for condensing the compressed gas, a pipe for supplying cooling fluid to said means, an expansion valve for transmitting the condensed fluid into said coil, a condenser valve controlling said pipe, automatic means for opening said condenser valve when said compressor is started and for locking it open and further operative when the power driving said compressor exceeds a predetermined limit to further open said condenser valve, to lock it open and close it when said compressor is stopped.
29. In combination an expansion coil, a compressor to draw gas therefrom and to compress the same, an electric motor for driving said compressor, fluid cooled means for condensing the compressed gas, a pipe for supplying cooling fluid to said means, an expansion valve for transmitting the condensed fluid into said coil, a condenser valve controlling said pipe, automatic means for applying electric power to open said condenser valve when said motor is started and for locking it open, when the power driving said compressor exceeds a predetermined limit for further opening said condenser valve, and for closing it when said motor is stopped.
30. In combination an expansion coil, a compressor to draw gas therefrom and to compress the same, an electric motor for driving said compressor, fluid cooled means for condensing the compressed gas, a pipe for supplying cooling fluid to said means, an expansion valve for transmitting the condensed fluid into said coil, a condenser valve controlling said pipe, automatic means for applying electric power to open said condenser valve when said motor is started and for locking it open, when the power driving said motor exceeds a predetermined limit for further opening said condenser valve and locking it open, and for closing it when said motor is stopped.
